UNITED STATES PATENT OFFICE

CARL KOZE, OF NEWARK, NEW JERSEY.

HINGE FOR VANITY BOXES AND THE LIKE.

Application filed June 19, 1924. Serial No. 721,056.

To all whom it may concern:

Be it known that I, CARL KOZE, a citizen of the United States, residing at Newark, in the county of Essex and State of New Jersey, have invented certain new and useful Improvements in Hinges for Vanity Boxes and the like, of which the following is a specification.

This invention relates to improvements in 10 hinges for vanity boxes and similar containers which are made of sheet metal, although the principles of the invention may find embodiment in other structures where parts are hingedly connected.

15 In the ordinary vanity box the wall of the body of the box and the rim of the lid are formed with interfitting pintle lugs through which is fitted a wire pintle pin. This ordinary construction, however, presents the 20 disadvantage that the hinge connection is liable to become sprung if any undue strain is placed thereon accidentally, or the pin is liable to become bent, thereby interfering with the proper closing of the lid, or the pin

25 is liable to become completely disengaged from the pintle lugs, thereby requiring its replacement, or, if actually lost, rendering the box unfit for further use. Furthermore, this pin constitutes a separate and distinct

30 element apart from the pintle lugs upon the body of the box and the lid and must be manufactured separately from these parts which, of course, adds to the cost of manufacture of the article as a whole. In view of 35 the disadvantages presented by the ordinary pin, the present invention has as its general object to provide a hinge connection between the body and lid of a receptacle such as a vanity box, which connection will be of such 40 nature as to overcome the disadvantages above outlined.

Another object of the present invention is to entirely dispense with the employment of a pintle pin in a hinge connection of the 45 class mentioned, thus eliminating the cost of labor and material incident to the provision of such a pin.

The ordinary vanity box which has its 50 lid hinged in the usual manner as above described, presents the further disadvantage that the hinge projects beyond the circumferential surface of the box and lid so that when the box is carried in a handbag, which is of delicate material, the hinge is liable to wear a hole in the bag or mutilate the lining of the bag. It is, therefore, another

important object of the present invention to provide a hinge for the purpose stated which will be flush with the circumferential surface of the box thereby permitting the box 60 to be smooth surfaced throughout its entire exterior and completely obviating the wear and mutilation of the handbag in which the box may be carried.

In the accompanying drawings: 65

Figure 1 is a perspective view of a vanity box equipped with the hinge embodying the present invention.

Figure 2 is a vertical sectional view taken substantially on the line 2-2 of Figure 1, 70 looking in the direction indicated by the arrows.

Figure 3 is a similar view taken on the line 3-3 of Figure 1, looking in the direction indicated by the arrows, 75

Figure 4 is a transverse sectional view taken substantially on the line 4-4 of Figure 2, looking in the direction indicated by the arrows.

In the drawings the numeral 1 indicates in general the body of a flat circular vanity case which is formed of sheet metal, and the numeral 2 indicates in general the lid of the case, which is likewise formed of sheet metal, the body of the case 80 or box having its circumferential wall 3 formed with the usual inward offset 4 about which the rim 5 of the lid 2 is designed to fit when the lid is closed, so that the exterior surface of the lid will be flush with 90 the exterior surface of the wall of the body 1.

The wall 3 of the body of the box is stamped or otherwise acted upon to provide an approximately cylindrical seat 6 having an open side presented at the exterior of the wall and indicated by the numeral 7, and having closed ends indicated by the numeral 8. Initially, these ends 8 are of 95 flat form.

The lid 2 has its rim 5 provided with a depending extension 9 which is of a width substantially equal to the internal length of the seat 6, and this extension 9 has its lower portion rolled to provide a hollow cylindrical open-ended pintle lug indicated by the numeral 10, the lug being located at the inner side of the said extension 9 and the outer surface of the said extension being flush with the outer surface of the rim 5. The pintle lug 10 is of a diameter to fit snugly and yet rotatably within the seat 105

6 and in assembling the lid with the body of the box, the lug is so disposed. The assemblage of the parts is completed by indenting the closed ends 8 of the seat 6 as 5 indicated by the numeral 11, so as to provide studs 12 which project into the ends of the pintle lug 10, in the manner clearly shown in Figures 2 and 4 of the drawings. The studs 12 are of approximately conoidal 10 form, and are exteriorly of a diameter to snugly fit within the ends of the pintle lug 10 and yet permit of free rotation of the said pintle lug within the seat and, at its ends, about the said studs. In this 15 manner, without the employment of the usual pintle pin, a direct hinge connection is provided between the lid and the body of the box. The connection is such that the parts will not become separated even 20 though they be subjected to considerable strain, and, furthermore, due to the relatively close fit of the pintle lug 10 in the seat 6 and the relatively snug engagement of the studs 12 in the open ends of the said 25 pintle lug, the hinge connection is a firm one as distinguished from the loose and insecure hinge connection ordinarily employed. Likewise, there is just sufficient frictional contact between the mutually engaged 30 parts of the hinge to insure of the lid of the box remaining in open position when so swung, so that if a mirror is provided in the lid, the one using the box may use of the mirror without the interruption 35 incident to dropping of the lid to closed position, which would be likely to occur if the hinge connection were of the ordinary type.

In order that the extension 9 which, in 40 fact, constitutes a shank for supporting the pintle lug 10, may be housed substantially flush with the exterior surface of the wall 3 of the body of the box, the said wall, immediately above the open side 7 of the seat 6, is struck in, as at 13, to provide a shallow recess 14 of a width equal to the

width of the said shank 9 and designed to accommodate said shank when the lid is in closed position, as clearly shown in Figures 1 and 2 of the drawings. While the 50 studs 12 are shown as substantially of conoidal form, that is to say, more or less rounded exteriorly, they may be formed to approximately conical form, if this should be desirable. 55

In the illustrated embodiment of the invention, the two members are integral with the body and lid of the box and formed directly from the material of the said body and lid. However, it will be understood that the invention is not to be restricted to this precise embodiment for the socket and pintle lug members might be formed separate from the body and lid respectively and secured to the said body and lid. 60 65

Having thus described the invention, what I claim is:

1. A sheet metal hinge comprising a member in the form of a substantially cylindrical hollow seat open at one side, a member in the form of a hollow, substantially cylindrical, open-ended pintle lug having a shank, the pintle lug being rotatably received in the seat with the shank extending through the open side of the latter, and means integral with the ends of the seat engaging in the open ends of the pintle lug. 70 75

2. A sheet metal hinge comprising a member in the form of a substantially cylindrical hollow seat open at one side, the said seat having closed ends, and a member in the form of a hollow substantially cylindrical, open-ended pintle lug having a shank, the pintle lug being rotatably received in the seat with the shank extending through the open side of the latter, the said ends of the seat having portions engaging in the open ends of the pintle lug. 80 85

In testimony whereof I affix my signature.

CARL KOZE. [L. s.]
